(57) **CLAIM**

The ornamental design for an air freshening device, as shown and described.

DESCRIPTION

FIG. 1 is a front perspective view of an embodiment of an air freshening device;

FIG. 2 is a front view thereof;

FIG. 3 is a left view thereof;

FIG. 4 is a back view thereof;

FIG. 5 is a right view thereof;

FIG. 6 is a top view thereof; and,

FIG. 7 is a bottom view thereof.

The broken lines shown in the drawings depict portions of the air freshener device and form no part of the claim.
